INVENTOR
Joseph M. Merrill
BY
Frank L. Ober
ATTORNEY

UNITED STATES PATENT OFFICE.

JOSEPH M. MERRILL, OF MONTCLAIR, NEW JERSEY.

PERFUME DISPENSER.

Application filed August 7, 1923. Serial No. 656,219.

To all whom it may concern:

Be it known that I, JOSEPH M. MERRILL, a citizen of the United States, residing at Montclair, in the county of Essex, State 5 of New Jersey, and having a post-office address at No. 3 Upper Mountain Avenue, Montclair, New Jersey, have invented certain new and useful Improvements in Perfume Dispensers.

10 My invention relates to an improved perfume dispenser, and my object is to provide a convenient, effective and attractive device for the purpose. The device is of metal, and may be suitably ornamented to 15 present an attractive appearance. It can be readily filled and the perfume dispensed therefrom by capillarity, as will be explained.

In order that the invention may be better 20 understood, attention is directed to the accompanying drawing forming part of this specification, and in which:

Fig. 1, is a longitudinal sectional view showing the two tubular sections engaged 25 together before locking the joint between them; and

Fig. 2, a side elevation.

In both of these views corresponding parts are represented by the same numerals.

30 The device utilizes two tubular sections, a body part 1, and an end section 2, tapered at 3, as shown.

The body 1 is provided with a cap or closure 4 held in place in any suitable way, 35 as by friction. By removing this cap a fresh supply of perfume may be introduced within the device. Near its other end the body 1 is formed with a bead 5, beyond which is a somewhat contracted neck 6 to restrict the flow of the perfume from the 40 body part 1. The end section 2 is pro-

vided with an enlarged portion 7 which receives the bead 5 (as in Fig. 1) and which is crimped or spun upon the bead (as in Fig. 2) to hold the two sections firmly together. In the end section 2 is a spring 8 placed therein before the parts are assembled and the outer end of said spring connects with a pin 9 loosely fitting the mouth of the tapered portion 3.

Surrounding the pin 9 is a cord 10 or other flexible material, which engages the bore of the tapered portion 3, to make a tight seal.

In the operation, the pin is pressed 55 against the handkerchief or other fabric or surface to be perfumed and a drop or two of the perfume runs out. The action seems to be due largely to capillarity, the perfume being drawn out through the restricted opening between the pin 9 and the mouth of the tapered portion 3.

Having now described my invention, what I claim as new therein and desire to secure 65 by Letters Patent, is:

A perfume dispenser, comprising a body portion having a bead and a contracted neck, a tapered end portion engaged over and around said bead, a spring engaging said body portion and surrounding said contracted neck and adapted to normally close a valve located in the mouth of the tapered end, and a pin on said valve for opening the valve when the pin is pressed against the surface to be perfumed, substantially 70 as set forth.

This specification signed and witnessed this 31st day of July, 1923.

JOSEPH M. MERRILL.
